UNITED STATES PATENT OFFICE.

BROE J. LINDGREN, OF BUFFALO, NEW YORK, ASSIGNOR TO NIAGARA MACHINE & TOOL WORKS, OF BUFFALO, NEW YORK, A CORPORATION OF NEW YORK.

BARREL-SEAMING MACHINE.

Application filed April 25, 1921. Serial No. 464,075.

To all whom it may concern:

Be it known that I, BROE J. LINDGREN, a citizen of the United States, residing at Buffalo, in the county of Erie and State of New York, have invented new and useful Improvements in Barrel-Seaming Machines, of which the following is a specification.

This invention relates to a machine for forming seamed joints between the body and heads of a sheet metal barrel or cask and has for its object the production of a machine for this purpose whereby the seaming operations may be effected efficiently and expeditiously and the working parts may be quickly and easily adjusted to suit barrels varying in length and diameter, as well as varying in the form of the seam, and also to permit of readily taking up wear and effect necessary adjustments when assembling the machine ready for operation.

In the accompanying drawings: Figure 1 is a fragmentary side elevation of a duplex double seamer for double seaming both ends of a sheet metal barrel or cask at one operation. Figure 2 is a vertical transverse section of the same, on an enlarged scale, taken on line 2—2, Fig. 1, but showing the barrel which is being seamed in dotted lines. Figures 3, 4 and 5 are vertical sections taken on the correspondingly numbered lines in Fig. 2. Figure 6 is a horizontal section taken on line 6—6, Fig. 4. Figure 7 is a perspective view of one of the seaming tools or rolls and associated parts in a dismembered condition. Figure 8 is a similar view of one of the spindles supporting a seaming roll and associated parts. Figure 9 is a fragmentary sectional view showing the drum or body and the head of a barrel mounted on a chuck preparatory to seaming them together. Figures 10 and 11 are similar views showing the successive operations of curling together the co-operating flanges of the drum and head and then tightening the same by means of the seaming rolls. Figure 12 is a fragmentary longitudinal section, on an enlarged scale, of the mechanism for shifting the movable standard for gripping and releasing the barrel which is being seamed. Figures 13 and 14 are vertical sections, on an enlarged scale, of the valve which controls the movement of pressure medium to and from opposite ends of the cylinder of the standard shifting mechanism.

Similar characters of reference indicate

corresponding parts throughout the several views.

The barrel or cask which is to be operated upon by my improved seaming machine, for connecting the drum and heads thereof, may be variously constructed but the barrel shown in the drawings as an example of one capable of being produced by this machine comprises a cylindrical body or drum 20 of sheet metal, and two disk-shaped heads 21 of sheet metal secured to opposite ends of the drum. The drum is provided at its opposite ends with integral laterally extending flanges 22 and each of the heads is provided at its edge with an outwardly projecting annular rim 23 which is connected integrally at its inner edge with the head, and an annular flange 24 projecting laterally from the front edge of the rim and formed integrally therewith. In the operation of seaming the drum and heads of a barrel, each head is placed on the supporting ring 25 of a rotary chuck so that the front face 26 of the ring bears against the outer side of the head and the periphery 27 of the same bears against the inner side of the rim, and the drum is engaged on the inner side of each end with the outer side of the rim of one of the heads while the adjacent flange of the drum engages its outer side with the inner side of the flange of the respective head, as shown in Fig. 9. After the drum and heads have been thus assembled and the same are rotating about the axis of the barrel, both ends of the latter are presented to two primary or preliminary seaming rolls 28 each of which is provided on its periphery with a preliminary seaming groove 29 which is adapted to rotate in engagement with the flanges of the drum and head at one end of the barrel and produce a preliminary curl or partial interlock of the same, as shown in Fig. 10. After the first or preliminary step in the operation of seaming the heads and drum of the barrel together has been accomplished, and while the barrel is rotating with the chucks, the partly seamed flanges of the drum and heads are engaged by the final or finishing grooves 30 on the periphery of two final or finishing seaming rolls 31, which rotate in engagement with these flanges and operate to press the same flat and cause the same to engage firmly with each other and finish the interlocking en-

gagement of the same, as shown in Fig. 11, and produce a tight joint therebetween.

In its general organization, the machine which embodies the means for rotatably supporting the barrel and operating the seaming rolls is constructed as follows:

The main frame of the machine comprises a horizontal base 32 and two standards 33, 34, mounted on the front and rear ends of the base. The front standard 33 is preferably fixed on the base while the rear standard 34 slides at its lower end on a guideway or track 35 upon which the same is movable lengthwise of the machine to permit of adapting the same to the manufacture of barrels of different lengths. 36, 37 represent front and rear chuck shafts or spindles which are arranged horizontally and lengthwise in line, the front shaft 36 being journaled in a suitable bearing in the lower part of the front standard and the rear chuck shaft 37 being journaled in a suitable bearing in the lower part of the rear standard but held against lengthwise movement therein, for instance, by a collar 371 secured to the adjacent part of the rear standard and engaging with a circumferential groove 372 in the rear chuck shaft, as shown in Fig. 12. Each of these chuck shafts is provided at its inner end with a chuck disk 38 upon which one of the supporting rings 25 is removably supported by engaging the latter with an annular rabbet-shaped seat 39 on the periphery of this disk, said ring and disk together forming the main elements of a chuck for rotatably supporting one end of a barrel.

40 represents the main driving shaft of the machine which is journaled horizontally and lengthwise on the base and provided with front and rear pinions 41, 42, which mesh with front and rear gear wheels 43, 44, on the outer ends of the chuck shafts 36, 37. The driving shaft may be operated by power from any suitable source with which the same may be connected by any approved or usual clutch or coupling device. The front chuck shaft and the parts mounted thereon are held against longitudinal movement. The rear chuck shaft is however capable of longitudinal movement for the purpose of advancing or retracting the chuck mounted thereon and permitting the barrel to be seamed to be clamped between the front and rear chucks while effecting the seaming operations thereon and to release the same after the seaming operations have been completed. This advancing and retracting motion of the rear standard, chuck and chuck shaft may be accomplished by any suitable means but preferably by a fluid operated motor which is constructed and operated as follows:

105 represents a shifting cylinder which is mounted lengthwise in the lower part of the

rear standard so as to move therewith and having ports 106, 107 in its front and rear heads. 108 is a stationary piston arranged within the shifting cylinder and secured to the front end of a piston rod 109 which extends through a stuffing box in the rear head of the shifting cylinder and connected at its rear end with a bracket 110 which forms part of the stationary frame of the machine. 102 represents the casing of a four-way controlling valve whereby the entrance and exit of the pressure fluid to and from opposite ends of the shifting cylinder is controlled. This casing has front and rear delivery ports 111, 112, a supply port 113 and an exhaust port 114 arranged equidistant about its center and connected respectively with a pipe 115 leading to the front port of the shifting cylinder, with a pipe 116 leading to the rear port of the shifting cylinder, with a pipe 117 leading to a source of supply of pressure medium, such as water under pressure, and with a waste pipe 118 leading to a sewer or other convenient place. Within the valve casing 102 is arranged a rotary plug 119 which when turned in one position connects the pressure supply pipe with the front end of the shifting cylinder and the waste pipe with the rear end of the same, as shown in Figs. 1, 12, 13, while upon turning this plug into another position, as indicated in Fig. 14, the pressure supply pipe will be connected with the rear end of the shifting cylinder and the waste pipe will be connected with the front end of the same. By thus alternately turning the plug of the controlling valve in opposite directions the shifting cylinder and the rear chuck and associated parts operatively connected with this cylinder will be moved forwardly and backwardly so as to grip the barrel to be seamed between the chucks and to release the same after this seaming operation.

Any suitable means may be provided for operating the controlling valve, those shown in the drawings being suitable and comprising a valve shaft 120 arranged lengthwise on one side of the base of the frame and journaled in suitable bearings on the same and provided with front and rear rock arms 121, 122, a rear intermediate elbow lever 123 pivoted on the rear part of the base and having its lower arm connected by a link 124 with the rear rock arm 122, a valve arm 125 connected with the stem 126 of the valve plug 119 and connected by a link 127 with the upper arm of the elbow lever 123, and a hand operated front elbow lever 128 pivoted on the front part of the base and having its lower arm connected by a link 129 with the front rock arm 121, as shown in Figs. 1 and 2. Adjacent to the hand lever 128 is arranged another hand lever 130 for operating the clutch 131 which couples and uncouples the driving shaft 40 and the driv-

ing means in any approved or usual manner. This valve mechanism is organized that the water or other pressure medium continues to press the rear standard forwardly and hold the rear standard against the barrel during the operation of seaming the same and thus insuring the rotation of the barrel, but after the controlling valve is reversed manually, the water pressure will 5 first move the rear standard backwardly to release the barrel and thereafter the plug of the controlling valve will be automatically shifted into its central position so as to cut off the pressure medium from both ends of 10 the shifting cylinder and thus bring the rear standard to a standstill. This automatic shifting of the controlling valve plug into its neutral position is due to the fact that this valve moves rearwardly with the rear standard 15 while the intermediate rock lever 123 for the time being is stationary, thereby causing the link 127 which acts as an abutment to gradually turn the controlling valve plug from its rearwardly turned position, in 20 which the pressure water moves the rear standard backwardly, to its neutral position, in which the pressure medium is cut off from both ends of the shifting cylinder. 25

In order to permit the rear chuck shaft 30 to move lengthwise and still maintain a driving connection between the same and the rear gear wheel 44, the latter is splined on the rear chuck shaft and journaled on an adjacent block 45 of the base so that this 35 gear wheel is free to turn but held against moving lengthwise with the rear chuck shaft. 40

Adjacent to the inner side of the upper part of each standard are arranged one of 45 the preliminary seaming rolls 28 and one of the finishing rolls 31, these rolls being arranged above the adjacent chuck and in spaced, relation circumferentially of the same, so that these rolls may engage independently of each other with the flanges of 50 the drum and head on the corresponding end of the barrel for producing the successive operations to curl and finish the seam joint on the respective end of the barrel. 55

Each of these rolls is so mounted that the same is moved periodically toward and from the flanges on the respective ends of the barrel and the same is also capable of bodily adjustment both radially and also 60 lengthwise of the axis of the barrel for adapting this roll to the flanges of the barrel, to permit of seaming of barrels of different lengths and also to originally adjust the machine and also take up wear in the same. In 65 its preferred embodiment the mechanism whereby this is accomplished is constructed as follows:

46 represents a main slide which moves radially in ways 47 on the inner side of the 65 upper part of each standard, the slides of the

preliminary and finishing rolls on the same standard being preferably arranged on opposite sides of a vertical line extending through the axis of the chucks and driving shaft and said slides converging downwardly, as shown in Fig. 2. The downward motion of these slides carrying the preliminary and finishing rolls is produced by means of cams 48, 49, which engage with anti-friction rollers 50, 51 on the upper ends of these slides, respectively, and which are mounted on cam or seamer shafts 52, 53, journaled horizontally and lengthwise in bearings on the upper parts of the standards. The cams next to the front standard 33 are 70 secured to the cam shafts but the cams next to the rear standard 34 are splined on the cam shafts, so as to turn therewith but the same are compelled to move lengthwise 75 on these shafts with the rear standard when the latter is moved lengthwise of the machine. Motion may be transmitted to these cam shafts in any suitable manner, this being accomplished for example by the means which are shown in the drawings and 80 which comprise a counter or jack shaft 54 journaled in the upper part of the front standard between the cam shafts and provided with an intermediate gear wheel 55 meshing with gear wheels 56, 57, on the cam 85 shafts, an upper intermediate shaft 103 journaled in the front standard and provided with a pinion 58 meshing with a gear wheel 59 on the counter shaft, and a lower intermediate shaft 60 journaled in the front standard and provided with a pinion 61 meshing with a gear wheel 62 on the upper intermediate shaft and also provided with a gear wheel 63 meshing with a pinion 64 90 on the companion chuck shaft, as shown in 95 Figs. 1, 2 and 3.

The return or outward movement of each main seaming roll slide is effected by a retracting spring 65 arranged in a pocket 66 in the adjacent part of the respective standard and bearing at one end against the bottom of this pocket and its other end against a lug 67 on this slide, said spring being held in position by a retaining rod 68 passing through said spring and secured at one end to said lug while its other end is guided in an opening 69 in the bottom of said pocket. 100

Upon each of the main slides is mounted a carrier or holder upon which is adjustably and rotatably supported one of the seaming rolls. This carrier is preferably of inverted U-form having front and rear arms 70, 71, the rear arm being provided with a dovetail guide rib 72 which engages slidingly 105 with a correspondingly-shaped guideway 73 on the outer side of the companion main slide 46. Adjustment of the carrier on its main slide is effected in a radial direction 110 relative to the axis of the chucks by means 115

of an adjusting screw 74 engaging with its intermediate part with a threaded opening in the carrier while its ends are journaled on the main slide, so as to be capable of turning thereon but compelled to move radially therewith. Each of the seaming rolls is arranged between the front and rear arms of one of the carriers and journaled by bearing rollers 75, or otherwise, on the 10 enlarged central part 76 of a cylindrical spindle or axle, the reduced front and rear ends 77, 78 of which are supported on the front and rear arms of the respective carrier. The front and rear sides of each 15 seaming roll are engaged by front and rear retaining disks 79, 80 which confine the bearing rollers between this roll and the axle and which engage with the outer and inner shoulders 81, 82 formed on the 20 axle between the enlarged central part and the reduced end parts thereof, as shown in Figs. 4 and 6. The front end of each roll axle is arranged in a front bushing or sleeve 83 which has a smooth periphery and is 25 capable of turning and sliding lengthwise in a smooth bored opening 84 in the front arm of the respective carrier, and the rear end of this axle is arranged in a rear bushing or sleeve 85 which latter has an external 30 screw thread 86 engaging with an internally threaded opening 87 in the rear arm of the respective carrier. The front bushing and retaining disk are compelled to turn together by coupling lugs or keys 88 arranged 35 on the front side of the front disk and engaging with recesses 89 in the rear end of the front bushing, and the rear disk and bushing are compelled to turn together by coupling lugs 90 arranged on the rear side 40 of the rear disk and engaging with recesses 91 in the front end of the rear bushing. The latter is also coupled with the axle so as to be compelled to turn therewith by a key 92 arranged on the rear part of the axle and engaging with a recess 93 in the bore 45 of the rear bushing. On the front end of the front bushing and the axle is mounted an adjusting disk or wheel 94 which is connected with the axle by a screw 95. The 50 wheel is provided on its inner or rear side with a diametrical groove 96 which engages with coupling lugs 97 on the front end of the axle and coupling lugs 98 on the front end of the front bushing. By means of this construction a turning movement of the 55 wheel 94 in either direction will cause the axle, seaming roll and the other parts mounted thereon to move either forwardly or backwardly as a unit and thus permit of adjusting the seaming roll to the required 60 position for properly operating on the flanges of the head and barrel for producing a seamed joint between the same, while at the same time preserving the proper condition of the bearing for the seaming roll,

so as to enable the same to operate most efficiently and accurately.

For the purpose of retaining the seaming roll in its adjusted position, a locking device is provided which preferably consists of a 70 locking catch 99 guided in a lug 100 on the front side of the respective carrier and held by a spring 101 yieldingly in engagement with one or another of an annular row of notches 104 in the periphery of the locking 75 wheel, as shown in Figs. 2 and 4.

The operation of seaming a barrel is as follows:

The operator places a barrel drum and its heads, which have previously been assembled, between the two chucks and then operates the controlling valve, so as to cause the rear chuck to advance and clamp the barrel between the front and rear chucks, and thereafter the barrel will begin to rotate, 85 inasmuch as the chucks rotate constantly while the machine is in operation. Immediately thereafter the cam shafts on the front and rear standards begin to rotate. These cam shafts are so timed that the cam 90 shaft of the preliminary seaming rolls causes the cams thereon to first depress both of these rolls and hold the same in this position a sufficient length of time to enable these rolls to effect the preliminary seaming 95 or curling of the drum and head flanges at both ends of the barrel in the manner indicated in Fig. 10. The preliminary cams then permit the return springs of the preliminary slides to retract the latter so that 100 the rolls thereon are disengaged from the barrel flanges, after which the finishing cams adjacent to both standards cause the slides of the finishing rolls to depress the latter into engagement with the flanges at both 105 ends of the barrel and retain the same in this position a sufficient length of time to enable them to complete the formation of the seams thereon, after which the slides of the finishing rolls are again retracted 110 for carrying the same into their inoperative position. The cycle of operations is now completed and at this time the rotation of the seamer cams is preferably arrested 115 automatically by any suitable or approved means usually employed for this purpose in this type of machine. The finished barrel is now removed from the chucks and replaced by an unseamed barrel preparatory 120 to effecting another cycle of operations.

This machine permits of effecting the seaming of barrels in this manner expeditiously and efficiently and the same can be readily adapted for seaming barrels of various lengths and diameters and thereby enables barrels of this character to be produced at comparatively low cost.

I claim as my invention:

1. A barrel seaming machine comprising 125 a main frame, means for rotatably support-

ing a barrel which is to be seamed in said frame, a seaming roll movable toward and from said barrel and means for supporting said roll including a carrier movable laterally toward and from the barrel, an axle which is adjustable on said carrier parallel with the axis of said barrel and which has an enlarged central part on which said roll is journaled, and retaining disks arranged on said axle and engaging opposite ends of the enlarged central part thereof and also engaging with opposite sides of said roll.

2. A barrel seaming machine comprising a main frame, means for rotatably supporting a barrel which is to be seamed in said frame, a seaming roll movable toward and from said barrel, and means for supporting said roll including a carrier movable laterally toward and from the barrel, an axle which is adjustable on said carrier parallel with the axis of said barrel and which has an enlarged central part on which said roll is journaled, retaining disks arranged on said axle and engaging opposite ends of the enlarged central part thereof and also engaging with opposite sides of said roll, a front bushing mounted on the front end of said axle and compelled to turn with the same and the adjacent front retaining disk and having a smooth periphery turning in a smooth opening in said carrier, a rear bushing mounted on the rear end of said axle and coupled with the axle and the rear retaining disk and having an external screw thread engaging a threaded opening in the carrier, an adjusting wheel coupled with the axle and the front bushing and provided with an annular row of notches, and a catch mounted on the carrier and adapted to engage with one or another of said notches.

3. A barrel seaming machine comprising a main frame, means for rotatably supporting a barrel which is to be seamed in said frame, a seaming roll movable toward and from said barrel, and means for supporting said roll including a carrier movable laterally toward and from the barrel, an axle which is adjustable on said carrier parallel with the axis of said barrel and which has an enlarged central part on which said roll is journaled, retaining disks arranged on said axle and engaging opposite ends of the enlarged central part thereof and also engaging with opposite sides of said roll, a front bushing mounted on the front end of said axle and compelled to turn with the same and the adjacent front retaining disk and having a smooth periphery turning in a smooth opening in said carrier, and a rear bushing mounted on the rear end of said axle and coupled with the axle and the rear retaining disk and having an external screw thread engaging a threaded opening in the carrier.

4. A barrel seaming machine comprising a main frame, means for rotatably supporting a barrel which is to be seamed in said frame, a seaming roll movable toward and from said barrel, and means for supporting said roll including a carrier movable laterally toward and from the barrel, an axle which is adjustable on said carrier parallel with the axis of said barrel and which has an enlarged central part on which said roll is journaled, retaining disks arranged on said axle and engaging opposite ends of the enlarged central part thereof and also engaging with opposite sides of said roll, a front bushing mounted on the front end of said axle and compelled to turn with the same and the adjacent front retaining disk and having a smooth periphery turning in a smooth opening in said carrier, a rear bushing mounted on the rear end of said axle and coupled with the axle and the rear retaining disk and having an external screw thread engaging a threaded opening in the carrier, and an adjusting wheel coupled with the axle and the front bushing.

5. A machine for seaming heads at opposite ends of a drum of a barrel comprising two preliminary seaming rolls adapted to engage the heads and the drum at opposite ends of the barrel, two finishing seaming rolls also adapted to engage the heads and the drum at opposite ends of the barrel, and means for alternately moving the preliminary and finishing seaming rolls into engagement with said barrel, including preliminary slides supporting the preliminary rolls, finishing slides supporting the finishing rolls, cams for actuating said slides, a cam shaft upon which are mounted the cams which operate the preliminary seaming roll slides, and a cam shaft upon which are mounted the cams which operate the finishing seaming roll slides.

6. A machine for seaming heads at opposite ends of a drum of a barrel comprising two preliminary seaming rolls adapted to engage the heads and the drum at opposite ends of the barrel, two finishing seaming rolls also adapted to engage the heads and the drum at opposite ends of the barrel, and means for alternately moving the preliminary and finishing seaming rolls into engagement with said barrel, including preliminary slides supporting the preliminary rolls, finishing slides supporting the finishing rolls, cams for actuating said slides, a cam shaft upon which are mounted the cams which operate the preliminary seaming roll slides, a cam shaft upon which are mounted the cams which operate the finishing seaming roll slides, a frame upon which said shafts are journaled, a driving shaft, and means for transmitting motion from said driving shaft to said cam shaft, including a

frame, a seaming roll movable toward and from said barrel, and means for supporting said roll including a carrier movable laterally toward and from the barrel, an axle which is adjustable on said carrier parallel with the axis of said barrel and which has an enlarged central part on which said roll is journaled, retaining disks arranged on said axle and engaging opposite ends of the enlarged central part thereof and also engaging with opposite sides of said roll, a front bushing mounted on the front end of said axle and compelled to turn with the same and the adjacent front retaining disk and having a smooth periphery turning in a smooth opening in said carrier, a rear bushing mounted on the rear end of said axle and coupled with the axle and the rear retaining disk and having an external screw thread engaging a threaded opening in the carrier, an adjusting wheel coupled with the axle and the front bushing and provided with an annular row of notches, and a catch mounted on the carrier and adapted to engage with one or another of said notches.

countershaft geared to both cam shafts, and gearing operatively connecting said countershaft and driving shaft.

7. A machine for seaming heads on the ends of barrel drums comprising two standards one of which is movable relatively to the other, means mounted on said standards for seaming the heads and drums of barrels, chucks mounted on said standards and adapted to grip the heads and drums of barrels between them, means for moving one of said standards toward and from the other standard including a shifting cylinder mounted on the movable standard, a stationary piston arranged in said cylinder, and a valve mechanism for controlling the entrance and exit of a pressure medium to and from opposite ends of said cylinder and constructed to automatically cut off the pressure medium from said cylinder during the backward movement of the movable standard.

8. A machine for seaming heads on the ends of barrel drums comprising two standards one of which is movable relatively to the other, means mounted on said standards for seaming the heads and drums of barrels, chucks mounted on said standards and adapted to grip the heads and drums of barrels between them, means for moving one of said standards toward and from the other standard including a shifting cylinder mounted on the movable standard, a stationary piston arranged in said cylinder, a controlling valve having a casing provided with a waste port, a pressure supply port, and delivery ports leading to opposite ends of said cylinder, a rotary valve plug adapted to connect said delivery ports either with said pressure port or said exhaust port or to disconnect both delivery ports from said pressure port, and a rock arm moving with said plug and connected with a normally stationary abutment.

9. A machine for seaming heads on the ends of barrel drums comprising two standards one of which is movable relatively to the

other, means mounted on said standards for seaming the heads and drums of barrels, chucks mounted on said standards and adapted to grip the heads and drums of barrels between them, means for moving one of said standards toward and from the other standard including a shifting cylinder mounted on the movable standard, a stationary piston arranged in said cylinder, a controlling valve having a casing provided with a waste port, a pressure supply port, and delivery ports leading to opposite ends of said cylinder, a rotary valve plug adapted to connect said delivery ports either with said pressure port or said exhaust port or to disconnect both delivery ports from said pressure port, a valve rock arm connected with said valve plug, a normally stationary shifting lever, and a link connecting said valve arm with said shifting lever.

10. A machine for seaming heads on the ends of barrel drums comprising two standards one of which is movable relatively to the other, means mounted on said standards for seaming the heads and drums of barrels, chucks mounted on said standards and adapted to grip the heads and drums of barrels between them, means for moving one of said standards toward and from the other standard including a shifting cylinder mounted on the movable standard, a stationary piston arranged in said cylinder, a controlling valve having a casing provided with a waste port, a pressure supply port and delivery ports leading to opposite ends of said cylinder, a rotary valve plug adapted to connect said delivery ports either with said pressure port or said exhaust port or to disconnect both delivery ports from said pressure port, a valve rock arm connected with said valve plug, a rear rock lever connected with said valve arm, a front rock lever, a rock shaft, and front and rear rock arms arranged on said rock shaft and connected, respectively, with said front and rear rock levers.

BROR J. LINDGREN.
